[57] CLAIM

The ornamental design for a motor housing for a ceiling fan, as shown and described.

DESCRIPTION

FIG. 1 is a side, bottom perspective view of a motor housing for a ceiling fan showing the new design in full lines with the broken line showing of environmental association matter being for illustrative purposes only and forming no part of the claimed design. The environmental structure is partially removed to more fully reveal the design aspects of the motor housing.

FIG. 2 is a side, bottom perspective view of a motor housing showing the new design in full lines with the broken line showing of environmental association matter being for illustrative purposes only and forming no part of the claimed design;

FIG. 3 is an enlarged view of the motor housing;

FIG. 4 is an enlarged view thereof;

FIG. 5 is an enlarged left-side elevational view thereof; and,

FIG. 6 is an enlarged right side elevational view thereof.
